UNITED STATES PATENT OFFICE.

CHARLES E. GREENE, OF BANGOR, MAINE.

BEATER ENGINE.

1,424,399.

Specification of Letters Patent. Patented Aug. 1, 1922.

Application filed March 5, 1921. Serial No. 449,960.

To all whom it may concern:

Be it known that I, CHARLES E. GREENE, a citizen of the United States, residing at Bangor, county of Penobscot, and State of Maine, have invented certain new and useful Improvements in Beater Engines, of which the following is a specification.

This invention relates to beater engines for working up the stock used in the manufacture of paper, and particularly to the construction of the bed plates therefor. Such bed plates are subjected to tremendous pressure as the stock is worked thereover by the revolving beater knives, and this pressure not only tends to wear down the usual wooden fasteners for the bed plate but to wear down the bed plate itself. This develops inequalities in the surfaces of the fasteners and the bed plate so that said surfaces lie in different planes relative to each other. When this condition arises, it is the practice to plane off the exposed surfaces of the wooden fasteners in order to again bring said surfaces and the surface of the beater plate itself in the same plane. Aside from the inconvenience and loss of time which this involves, the wear produced by the stock being worked over the wooden fasteners rapidly causes the wood of the fasteners to become black. This is a serious defect in that it results in the introduction of black specks or blots into the stock and ultimately into the paper, and accordingly one of the objects of my invention is to prevent the introduction of these blots or specks in the final product.

I overcome these several disadvantages in existing structures by a form of bed plate and fastener in which wear of the fasteners and consequent specking of the stock is not only eliminated, but in which provision is made for taking care of the wear upon the bed plate itself so that the surface of the bed plate and the fasteners therefor may be readily maintained in coinciding planes, all in a construction of simple and practical form and one in which the bed plate itself is firmly clamped against unwarranted movement.

In the accompanying specification and drawings I have shown a form of my invention which I have found satisfactory in use and well adapted to the requirements of practical operation. Throughout the specification and drawings like reference char-

acter are correspondingly applied and in the drawings:

Fig. I is a plan view of a beater engine bed assembly in accordance with my invention.

Fig. II is a side elevation thereof.

Fig. III is a section on the line III-III of Fig. I.

Figs. IV, V, and VI are plan, side and end views, respectively, of the bed plate removed.

Figs. VII and VIII are detail views of the removable metallic fasteners for the bed plate.

Figs. IX and X are detail views of the wooden seats for the bed plate, and

Figs. XI and XII are transverse sections particularly illustrating the manner in which wear upon the bed plate is taken care of.

I have indicated at 1 a trough-like bed within which is clamped the bed plate 2 of the beater engine. Such plate consists of alternate strips of steel 2' and wood 2^a bolted together in the staggered arrangement shown in the drawings. The beater knives revolve transversely over the bed plate and work the stock against the corrugated surface thus presented by said strips 2' and 2^a.

The bed plate 2 rests upon the floor of the bed 1 between a pair of strips 3 which fix the position of said bed plate within the bed. Said strips 3 are confined between the side walls of the bed 1 and have their opposing edges shaped to conform to the staggered shape of the bed plate. The strips 3 are preferably of wood so that they may be planed off as the bed plate 2 wears down. The fasteners for the bed plate are disposed on either side of said plate and are simple angle-irons having their vertical portions 4 disposed against the side walls of the bed 1 with the lower edges thereof resting upon the strips 3, and having their horizontal portions 5 disposed in the same plane with each other and with the outer face of the bed plate 2. The opposing edges of said horizontal portions 5 are shaped to conform to the staggered shape of the bed plate. If desired, a shim 6 of proper thickness may be inserted between one of the surfaces 4 and the adjacent wall of the bed 1 to maintain the assembly tight.

Inasmuch as the fasteners 4 are of metal, they will not wear down under the action

of the stock and consequently will not discolor the stock. The wear of the bed plate itself with resultant disturbance of the co-planer disposition of the outer surfaces of the fasteners and bed plate is taken care of by the wooden strips, which may be planed off an amount equal to the amount worn away from the bed plate itself, and inasmuch as the fasteners rest upon said strips, their exposed surfaces are thus correspondingly lowered to coincide with the new level of the bed plate 1. I am thus able to take care of the wear which comes upon the bed plate in a construction in which the fasteners for the bed plate will not themselves wear down and hence will not cause discoloration of the paper stock.

Various modifications may be made in the form and construction of my device without departing from the spirit of my invention if within the limits of the appended claims.

What I therefore claim and desire to secure by Letters Patent is:

1. Bed plate construction for beater engines comprising a channeled bed and a bed plate, a pair of spaced position defining members of reducible thickness lodged within said bed upon either side of said bed plate and defining the position of said bed plate, and a pair of spaced bed plate fasteners having their outer surfaces normally disposed in the plane of the outer surface of the bed plate and supported upon said position defining members whereby to adjust themselves to new levels of the bed plate as the thickness of said position defining members is reduced, said fastener of a non-wearing material so as to prevent discoloration of the stock.
2. Bed plate construction for beater engines comprising a channeled bed and a bed plate, a pair of spaced position defining members lodged within said bed and between which the bed plate is disposed, said members reducible in thickness to correspond to reductions in the effective height of the bed plate, and a pair of spaced metallic bed plate fasteners having their outer surfaces normally disposed in a plane coinciding with the outer surface of the bed plate and supported upon said position defining members whereby to adjust them-

5 members whereby to adjust themselves to new levels of the bed plate.

3. Bed plate construction for beater engines comprising a channeled bed and a bed plate, a pair of spaced position defining members of reducible thickness lodged within said bed and between which the bed plate is disposed, and a pair of spaced metallic fasteners having horizontal portions normally disposed in the plane of the outer surface of said bed plate and having vertical portions supported upon the position defining members, whereby to adjust said horizontal portions to new levels of the bed plate as the thickness of the position defining members is reduced.

4. Bed plate construction for beater engines comprising a bed, a plate mounted thereon, a pair of spaced wooden members of reducible thickness within said bed upon either side of the bed plate and defining the position of said bed plate, and a pair of spaced metallic fasteners for said plate having their outer surfaces disposed in the plane of the outer surface of the bed plate, said fasteners supported upon said position-defining members whereby to adjust themselves to new levels of the bed plate as the thickness of said position defining members is reduced.

5. Bed plate construction for beater engines comprising a bed and a bed plate, a pair of spaced members lodged upon said bed upon either side of the bed plate and defining the position of said bed plate and reducible in thickness to correspond to reductions in the effective height of the bed plate, and a pair of spaced metallic fasteners for said bed plate having their outer surfaces normally disposed in the plane of the outer surface of the bed plate and supported upon said position-defining members whereby to adjust themselves to new levels of the bed plate as the thickness of said position defining members is reduced.

In testimony whereof I affix my signature in presence of two witnesses.

CHARLES E. GREENE.
